SPRING CUSHION CONSTRUCTION

Roy S. Jones, Anderson, Ind., assignor to The Barber Manufacturing Company, Anderson, Ind., a corporation

Application November 30, 1934, Serial No. 755,264

2 Claims. (Cl. 155—179)

This invention relates to a spring cushion structure suitable for upholstered chairs, davenport, and the like.

The chief object of this invention is to provide a structure which has all the advantages of the prior art as to cushioning and resiliency, and which in addition thereto, is constructed of a minimum number of parts and some of these so associated together that in addition to the aforementioned advantages, the present invention has the additional advantage that lateral movement of the spring supporting strap is substantially prevented.

The present invention inherently consists of two spaced rails which may be designated the front and rear rail of a davenport, settee, chair, or the like. Mounted on the front rail is a plate or bracket. Mounted on the back rail directly opposite is a similar, and in the preferred form of the invention, an identical bracket. A metal strap of resilient character has one end arranged to form one butt of a hinge.

One of the brackets has a cooperating arrangement adapted to receive a hinge pin for hingedly mounting the butt formed end of the strap. The opposite end of the strap in the preferred form, is provided with a pair of apertures, one at each corner and a pair of helicals, each having hooks formed on opposite ends, and lying in transverse planes, are associated at one end with the strap apertures and at the opposite end with the opposite plate or bracket.

To the strap is suitably secured in tandem relation the desired cushion coils and silencing means, if desired, may be associated with the strap and cushion coils for silencing the clicking of the coils on the strap. The upper ends of the cushion springs may be, if desired, associated with border wire or other means.

By the aforesaid arrangement, a relatively elongated hinge pin bearing is obtained at the hinge of the strap and a diverging tension support is obtained at the opposite end of the strap, which diverging tension arrangement serves to resist lateral movement of the strap when in use.

Positioning of the ends of the helicals in transverse planes provide in effect a universal connection between the adjacent rail and the apertured end of the strap permitting up and down movement under load and when the helicals are positioned parallel to each other, permits of lateral movement if that is desired in the completed spring cushion construction.

The full nature of the invention will be under-

stood from the accompanying drawing and the following description and claims:—

In the drawing, Fig. 1 is a top plan view of a portion of one form of frame structure, including the spring cushion arrangement embodying the invention, certain portions being broken away to illustrate other portions in detail.

Fig. 2 is a front to rear sectional view taken on line 2—2 of Fig. 1 and in the direction of the arrows, the full lines illustrating the normal position of certain of the parts when not under load and the dotted lines illustrating a position of some of these parts when subjected to load.

Fig. 3 is a perspective view of one of the hinge forming plates with the associated hinge pin or pintle mounted thereon.

Fig. 4 is a similar view of a portion of an identical plate with a portion of one of the helicals associated therewith.

In the drawing there is illustrated a main frame including a front rail 10 and a rear or back rail 11 suitably connected together as by side rail 13. A plate 14 is suitably secured to the front rail 10 by the screws 15 passing through the apertures 16 in said plate. Said plate includes a pair of projecting portions 17 in spaced relation, the spacing preferably being at least equal to the width of the metal strap, hereinafter to be described. The portions 17 are formed by slitting the plate as at 18 and the metal portion 30 between a pair of these slits is deformed to form a socket adapted to receive a hinge pin. Herein the hinge pin or pintle is in the form of an angular rod having the main body portion 19 and an angular end 20.

The strap 21 at one end is curled as at 22 to form a complementary socket which, when aligned with the two sockets formed by the portions 17, is adapted to receive the pintle 18 and thus hingedly support one end of the strap to the front rail. The opposite end of the strap in the preferred form of the invention, is apertured at each corner as at 23.

Suitably secured to the inside of the back rail is another plate 14, herein shown identical with the plate of the front rail. Screws 15 pass through apertures 16 in said plate for mounting the latter. The socket portions 17 are adapted to receive the semi-circular hook-like end 24 of a closely coiled helical spring 25, the opposite end of which is in the form of a similar semi-circular hook 26. This hook 26 is positioned in a plane substantially transverse to the plane of the hook 24 and the two hooks are in alignment with reference to the longitudinal axis of the helical.

35

40

50

55

The hook 26 is positionable in the aperture 23 in the strap with the mouth up.

As shown clearly in Fig. 1, this form of mounting, due to the fact that the spacing between the two portions 17 of the plate is at least equal to the width of the strap, there results a diverging relationship between the two helicals which yieldingly secure the nonpivoted end of the strap to the back rail. It will be noted that the hooks 10 24 permit swiveling about the axis of the sockets 17—that is, about a horizontal axis—and also the hooks 26 permit up and down movement of the strap relative to said hooks.

When the two springs 25 are positioned parallel 15 to each other and instead of plate 14 having the spacing equal to the strap spacing, said plate has its sockets spaced the same distance as the spacing between the apertures 23, then the two springs when thus connecting the strap to the rear rail 20 provide for universal movement. Preferably, however, the diverging relationship is employed because any tendency then of the load applied to the seat to move the strap laterally, will be resisted by one or the other of said divergingly 25 arranged springs.

In Fig. 2, the dotted line indicates in a general way, the position assumed by the strap and springs when subjected to load, such as a person sitting down. It will be observed this dotted position does not show the strap in alignment with a plane, but there is a slight bowing of the strap and this is permitted because the strap is resilient, although upon the release of load, it will assume a position coincident with a plane.

Herein the cushion construction is shown embodying a plurality of spaced double conical cushion springs 30. The strap 21 at the desired intervals is provided with slits 31 in paired and spaced relation and the intermediate portion 32 between each pair of slits is offset and forms a socket to receive the end turn 33 of the double coil spring. Thus, each cushion spring is rigidly anchored to the strap and the cushion springs are arranged in tandem and the desired spaced relation upon 40 said strap.

Merely as an example of one form of completed cushion construction, attention is invited to a border wire 34 which, by means of clips 35, is clampingly associated with the top coils 36 of the border arranged cushion springs. If desired, 50 suitable wire lacing or other type of lacing 37 may be associated with the several springs to form a unitary top structure. Such lacing is also associated with clips 38, if and when desired.

When the springs are subjected to load, it frequently happens the second bottom turn and sometimes even the third, of one or more of the cushion springs operatively bears on the strap 21. This creates a clicking action on the initial contact therewith. Consequently, in certain forms 60 of the invention, silencing means is provided and herein the same includes a fabric strip 40 which at each end has a sewed loop 41.

A clip 42 has its central portion nested in said loop and its ends 43 turned downwardly and 65 then inwardly toward each other in strap-embracing relation. The initial form of this wire clip is a straight portion and one end turned as illustrated. The straight portion is inserted through the loop. The hook end portion is positioned to nestingly receive the strap and the projecting opposite end is turned downwardly and then reversely toward the first mentioned hook end.

75 The silencing strip, as is clearly shown in Figs.

1 and 2, is interposed between the strap 21 and the second lowermost turn of the cushion spring and between the lowermost turn and the second lowermost turn of said cushion spring, since only a relatively small portion of the lowermost turn, which overlaps the strap, is in turn overlapped by the anchoring portions 32 of the strap. 5

Between cushion springs, similar clips 45 may be employed. Herein, the strip 40 is shown of lesser width than the strap 21, although the strip 10 may be of the same width and of greater width, if desired.

Longitudinal movement of the strip relative to the strap may be prevented by the end clips 42-43, having the portion 42 enclosed by the 15 loop 41 of said strip, and the loop bearing against the end anchoring portion 32 whenever longitudinal movement of the strip is to be positively prevented. However, as shown herein, the clips 42-43-45 normally are sufficient to relatively 20 fixedly secure the strip to the strap in the predetermined position and maintain the same therein.

It will be observed in the primary form of the invention, as well as the preferred form, that the 25 front and rear plates are identical and thus are interchangeable, and can be made by one die. This requires but a single part to be carried in stock. It is to be noted that forming the end of the strap with a curled socket forming portion, 30 provides a relatively elongated hinge bearing for the strap, thereby further eliminating the possibility of cocking of the strap about its hinge pivot. Also, the helicals 25 are reversible and can be interchanged end for end and also the 35 helicals are commercially identical.

To accommodate a plurality of manufacturers of upholstered chairs, settees, sofas, davenport, and the like, all that is necessary is that the metal strap material be carried in stock, cut to 40 the desired length and then one end formed with the curled socket, irrespective of the length of the strap, and the opposite end apertured as shown. The only modification to satisfy each manufacturer's requirements is the spacing between the adjacent pairs of slits 31 in said strap to 45 accommodate different sizes of cushion springs and to provide for the desired spacing between the tandem mounted springs to be associated with said strap. Thus, for the primary spring 50 manufacturer, this invention provides for the fabrication of the basic structure for any subsequent upholstery manufacturer to build upon and with a minimum number of parts and with a 55 minimum number of variations in operation.

The invention claimed is:

1. In a chair and the like, having a frame with a pair of spaced rails, a plurality of substantially parallel, relatively independent, flexible, spring supporting, metal straps and a plurality of 60 cushion coils suitably secured at their bases to each strap and in tandem relation, and suitably secured at their upper ends into a unitary arrangement, the combination of connecting means between one rail and the ends of all straps adjacent thereto and other connecting means between the opposed rail and the ends of said straps adjacent said opposed rail, one of said connecting means being resilient in character and the other being of hinge character, the connections at opposite ends of each strap including identical anchoring plates adapted for rail anchorage and each having a pair of axially aligned offset portions spaced apart approximately the width of a strap and projecting from one face of said 75

- plate, one end of the strap being curled for registration with the spaced portions of the adjacent plate, a hinge pin hingedly connecting the curled strap end and the adjacent aligned spaced portions, the other end of the strap having an aperture adjacent each corner, and a pair of helicals each having an end anchored to the strap through a corner aperture and its opposite end anchored to the adjacent offset portion of the adjacent plate, the resulting yielding connection being of diverging character for resisting lateral movement of the strap, the effective elongated hinge connection preventing tilting of the strap about a longitudinal axis of the same and reducing the unit load transmitted by each longitudinal element of the strap to the hinge pin.
2. The combination with a pair of opposed spaced rails, a spring supporting metal strap operatively associated at opposite ends with said rails, and a plurality of cushion coils suitably secured at their bases to said strap and in tandem relation, of a silencing strip extending longitudinally of the strap and interposed between the lowermost turn and the second lowermost turn of each of the cushion coils, the strap adjacent each cushion coil including a plurality of pairs of slits, the pairs of slits being longitudinally aligned and grouped in pairs, each pair group being diametrically associated with the bottom turn of a cushion coil, the intermediate portion of the strap between each pair of slits being offset from the face of the strap, the lowermost turn of the coil being interposed between said offset portion and the main body of the strap for coil anchorage, and C-clips embracing the strap and strip, one end of the silencing strip adjacent one end of the strap terminating in a loop, the juxtaposed clip being included in said loop and operatively associated with the immediately adjacent coil anchoring offset portion of the strap.
